CLAIM

The ornamental design for a cap for cosmetic product container, as shown and described.

DESCRIPTION

FIG. 1 is a top, front and left side perspective view of a cap for a cosmetic product container showing our new design, the container being drawn in phantom lines and forming no part of the new design;

FIG. 2 is a front elevational view thereof, the rear elevational view being identical;

FIG. 3 is a left side elevational view thereof, the right side elevational view being identical;

FIG. 4 is a top plan view thereof; and,

FIG. 5 is a bottom plan view thereof.
